Attorney

UNITED STATES PATENT OFFICE.

CHARLES O. ANDERSON, OF OMAHA, NEBRASKA.

ADJUSTING MEANS FOR RAILWAY BRAKES.

Application filed December 12, 1924. Serial No. 755,493.

To all whom it may concern:

Be it known that I, CHARLES O. ANDERSON, a citizen of the United States, residing at Omaha, in the county of Douglas and 5 State of Nebraska, have invented certain new and useful Improvements in Adjusting Means for Railway Brakes, of which the following is a specification.

My invention relates to railway brakes of 10 the class in which adjustments to compensate for wear of the brake-shoes are made by variations in the connected relations of a dead-lever and a fulcrum-member or guide for said lever. It is the object of my 15 invention to provide, in brake mechanism of this class, a simple and effective means for compensating in the brake connections for the variations in relative position of the brake-beam and the bolster or transverse 20 truck-member with which the dead-lever is connected through the medium of the dead-lever-guide.

A structure embodying my invention is illustrated in the accompanying drawings, 25 in which Fig. 1 is a longitudinal vertical section, partly diagrammatic, of a car-truck having my adjusting means applied to the brake-rigging thereof, Fig. 2 is a detail plan view of the dead-lever-guide and the 30 head of the dead-lever, Fig. 3 is a side view of the dead-lever and guide as adjusted for new brake-shoes, and on new equipment in which sagging of the brake-beam relative 35 to the bolster has not occurred, and Fig. 4 is a side view of the dead-lever and guide as adjusted for worn brake-shoes.

Referring to Fig. 1, there are represented portions of an ordinary brake-rigging as 40 applied to trucks of freight-cars, the principal members indicated in the figure being the wheels 10, the side-frame 11, a portion of the bolster 12, the brake-shoes 13, brake-beams 14 and 15, brake-hangers 16, the 45 brake-rod 17 by tension of which the brakes are applied, the live-lever 18, the dead-lever-guide 19, and the bottom-rod 20 which connects the lower ends of the live-lever and dead-lever. The dead-lever-guide 19 is pivotally connected with a lug 21 on the side 50 of the bolster 12, said guide is formed from a flat bar which is doubled to provide parallel sides spaced apart sufficiently to receive the upper end of the dead-lever between them, and in said parallel sides of the guide 55 are a series of holes 22 for the fulcrum-pin 23 which pivotally connects the end of the

dead-lever with the guide. All of the foregoing parts are of ordinary construction and will be understood to operate in the usual manner. In the ordinary construction, however, the dead-lever is a simple bar having three transverse holes or openings therein, namely, one at the lower end for receiving the pin by which the lever is connected with the bottom-rod, one at the lower 60 intermediate portion for receiving the pin by which the lever is pivoted upon the break-beam 15, and one at the upper end for receiving the fulcrum-pin 23 to connect the lever with the guide 19.

In my improved construction the lower portion of the dead-lever 24 is of the usual form and proportions, having therein the hole 25 for the bottom-rod connecting-pin 26, and the hole 27 for the brake-beam pivot-pin 28. At the upper end of the lever 24 a head 29 is formed integrally therewith, and in said head are a plurality of fulcrum-pin holes 30. Said holes 30 are arranged equidistantly from the hole 27 for the brake-beam pivot-pin 28, or with their centers upon an arc struck about the center of the hole 27. One of the holes 30 is centered upon a line extending longitudinally of the lever through the centers of the holes 25 and 27, thus corresponding in position with the hole for the fulcrum-pin 23 in the ordinary form of dead-lever, but each of the holes 30 is adapted to receive said fulcrum-pin 23, for establishing adjusted relations 80 of the lever and guide. Upon the side of the lever, near one edge and adjacent to the upper end on head 29, is a lug 31 which is preferably integral with the lever, as shown.

In brake-rigging of the class under consideration, the application of the brakes by tension upon the brake-rod 17 tends to move the upper fulcrumed end of the dead-lever toward the bolster, so that the guide 19 is under compression between the fulcrum-pin 23 and the pivot-pin 32 which connects the guide with the lug 12 on the bolster. It is desirable that the guide extend approximately horizontal, or, if it is inclined from a horizontal position, that the free end opposite 95 the pivot-pin 32 be at a level above the pivoted end, in order that the pressure of the dead-lever upon the guide may be exerted almost directly toward the lug 12, and thus have little if any tendency to swing the 100 guide about its pivoted end; and in new equipment the various parts of the brake-

rigging are so proportioned and arranged that the described relation of the parts will exist. It is found in practice, however, that in trucks which have been in use for a time 5 the position of the brake-beams relative to the bolster is changed, and that there is a sagging or dropping down of the brake-beams, so that the same and the dead-lever are lowered relatively to the bolster. The 10 sag or drop of the brake-beams is due to wear of the brake-hangers 16, and to various other causes which it is unnecessary to here enumerate. In Fig. 3 there is shown in full lines the normal relation of the dead-lever, dead-lever-guide, and bolster, and in the same figure there is indicated by dotted lines the relative position of the dead-lever 15 in old or worn equipment, wherein the sag or drop of the brake-beams has occurred. 20 When new brake-shoes are applied, the necessary slack or clearance between the brake-shoes and wheels is obtained by adjusting the dead-lever fulcrum to a point near the pivoted end of the guide, or usually so that 25 the fulcrum-pin 23 passes through the first hole 22 adjacent to the guide-pivot-pin 32. The result of such adjustment, in old or worn equipment wherein sag or drop of the 30 brake-beam has occurred, is to place the guide 19 in a downwardly inclined position such as indicated by dotted lines in Fig. 1, and in such position the pressure of the 35 dead-lever during application of the brakes is exerted laterally instead of longitudinally of the guide, to an extent tending to increase the angular displacement of the 40 guide, thus placing abnormal stresses upon the parts, causing distortion and bending thereof, and sometimes producing breakage 45 of parts and complete failure of the braking function.

With my improved construction the above described undesirable effects, resulting from sag or drop of the brake-beams relative to 50 the bolster, may be entirely avoided. Referring to Fig. 1 it will be seen that by reason of the inclined position of the dead-lever which is normally assumed when adjustment is made for applying new brake- 55 shoes, the laterally extending head 29 on said lever has an upward inclination, whereby one of the holes 30 in said head 29 will be in register with a corresponding hole 22 in the guide when the latter is raised to the 60 desired normal or approximately horizontal position; and that by insertion of the fulcrum-pin 23 in said registering holes such position of the guide may be maintained. It will be seen further that the provision of 65 the lug 31 on the side of the dead-lever will prevent accidental or careless connection of the dead-lever and guide in a manner such that the guide has a downwardly inclined position, as in such a position the guide and 70 said lug would interfere, it being obvious

from Fig. 1 that the guide would engage the upper edge of the lug before reaching the downwardly inclined position indicated by the dotted lines in said figure.

As all of the holes 30 in the head 29 are at the same distance from the hole 27 for the brake-beam pivot-pin 28, any of said holes 30 may be utilized for the fulcrum-pin 23, according to the amount of sag or drop of the brake-beam, without changing the 75 ratio of the brake-levers or affecting the operation of the brakes in any undesirable way. Adjustments of the dead-lever to compensate for excessive slack or clearance between the brake-shoes and the wheels, 80 may be made in the usual manner, by changing the fulcrum-pin 23 to engagement with the successive holes 22 toward the outer or free end of the guide, until at the maximum wear of the brake-shoes the dead-lever and 85 guide will be connected as represented in Fig. 4. In order to accommodate the increased width of the dead-lever resulting from the formation of the head 29 thereon, the length of the guide may be made greater 90 than usual, or for the extreme adjustments the lever may be reversed in position so that said head 29 extends toward instead of away from the bolster.

It will be noticed that as the dead-lever is adjusted toward the outer end of the guide it will assume a more nearly vertical position, so that the use of the additional holes 30 in the head 29 will be less effective in raising the guide from a downwardly inclined position, but the decreasing effectiveness in this respect is offset by the lifting of the head 29 due to the upward swing of the lever, and also to the fact that a slight downward displacement at the outer end of the guide will cause only a slight angular displacement instead of the large and objectionable angular displacement which would occur were the lever connected with the 100 guide near the inner end of the latter. 110

Now, having described my invention, what I claim and desire to secure by Letters Patent is:

1. In a railway-brake mechanism, the combination with a dead-lever-guide having a series of longitudinally spaced fulcrum-pin holes, and a frame-member to which one end of said guide is pivotally connected; of a dead-lever having a head at the end thereof adjoining said guide, said head having therein a plurality of fulcrum-pin holes spaced laterally of the lever-body and equidistantly from the brake-beam-pivot of the lever, said holes being adapted to register severally with some of the holes in the guide to receive a fulcrum-pin for connecting said lever and guide when the latter is in adjusted angular relations to the frame-member on which it is pivoted. 120

2. In a railway-brake mechanism, the com- 130

bination with a truck-bolster, a dead-lever-guide pivoted at one end to said bolster and having a series of fulcrum-pin holes spaced longitudinally thereof, a suspended brake-beam subject to variation in its vertical relation to said bolster, a dead-lever pivoted on said brake-beam and arranged to extend at an incline when one end thereof is adjacent to the pivoted end of said guide, and a fulcrum-pin for connecting said dead-lever and guide; of a head on said end of the lever adjoining the guide, said head having a plurality of fulcrum-pin holes spaced apart laterally of the lever and adapted to register severally with holes in the guide for receiving the fulcrum-pin to connect the lever and guide, whereby the guide may be main-

tained in adjusted relation to the bolster when the brake-beam varies in vertical relation to the bolster.

20

3. A structure as set forth in claim 1, including a member on the dead-lever engageable with the guide to prevent connection of the lever and guide when the latter is in an abnormal angular relation to the frame-member.

4. A structure as set forth in claim 2, including a lug formed on the side of the dead-lever adjacent to said head and adapted to engage the guide to prevent connection of the lever therewith when the guide is in abnormal angular relation to the bolster.
